MILK CARTON HOLDER

Joseph Varacek, Floral Park, N.Y.

Application October 24, 1957, Serial No. 48,225

Term of patent 7 years

(Cl. 58—26)

The figure is a perspective view of a milk carton holder, showing my new design.

The characteristic features of my design for the milk carton holder disclosed reside in the upright flat strap forming the spine having the handle and the spring loaded finger lever at the top thereof as shown.

I claim:

The ornamental design for a milk carton holder, as shown and described.
